UNITED STATES PATENT OFFICE.

THURE LARSSON, OF WORCESTER, MASSACHUSETTS, ASSIGNOR TO HIMSELF, WILLIAM E. D. STOKES, OF NEW YORK, N. Y., AND FRED A. JONES, OF WORCESTER, MASSACHUSETTS.

STOPPING MECHANISM FOR PLUNGER-ELEVATORS.

No. 888,515.

Specification of Letters Patent.

Patented May 26, 1908.

Application filed September 25, 1902, Serial No. 124,737. Renewed December 7, 1904. Serial No. 235,881.

To all whom it may concern:

Be it known that I, THURE LARSSON, a subject of the King of Sweden and Norway, residing at Worcester, in the county of Worcester and State of Massachusetts, have invented a new and useful Stopping Mechanism for Plunger-Elevators, of which the following is a specification.

This invention relates to that class of hydraulic elevators in which the elevator cars are directly actuated by vertically moving pistons or plungers.

The especial object of this invention is to provide a strong, simple, and efficient construction for stopping the elevator cars at the ends of their runs.

The invention consists of the parts and combinations of parts as hereinafter described and more particularly pointed out in the claims at the end of this specification.

In the accompanying drawing, Figure 1 is a fragmentary perspective view of sufficient parts of a plunger elevator to illustrate the application of my invention thereto, Fig. 2 is a sectional view showing the arrangement of parts within the plunger casing, Fig. 3 is a similar view illustrating a modified form of construction, and Fig. 4 is a detail sectional view taken on the line 4—4 of Fig. 3.

In an elevator of that class to which this invention relates, the elevator car is moved up and down by a piston or plunger which runs down into a casing set into the ground. The water supply is admitted near the top of the plunger casing, and the operation of an elevator of this class has heretofore only been controlled by a main valve, which admits water to the casing when the elevator is to be raised, and which permits water to escape from the casing when the elevator is to descend. To stop the elevator at the ends of its run, the stopping connections which have heretofore been employed in this class of constructions, have been arranged to operate the controlling valve. That is to say, in the ordinary constructions of this class, the hand controlling rope or other connection from the elevator car has heretofore usually been provided with stops or abutments for automatically closing the valve as the elevator approaches the ends of its run. The efficiency of these stopping connections as heretofore constructed, has been entirely dependent upon an automatic control of the valves, and in case the valves are rendered inopera-

tive for any reason, elevators of this class are liable to be carried up so that the end of the plunger will be driven up out of its casing, or, in some cases, the elevator car will not be properly stopped at the bottom of its run.

The especial object of this invention is to provide a construction for automatically stopping a plunger elevator which does not depend upon the operation of the controlling valve.

To accomplish this object, an automatic stopping mechanism for a plunger elevator constructed according to this invention, comprises shut-off connections inside the plunger casing. These shut-off connections are preferably arranged to move up and down with the plunger, and are controlled by the travel of the elevator car, so that when the car reaches the top of its run, the water pressure will be automatically cut off, and the motion of the car arrested without depending upon the operation of the supply valve. The same connections are also preferably employed for stopping the elevator car at the bottom of its run, although, if desired, additional stopping connections may be employed for bringing the car to rest when it reaches its lowest position.

Referring to the accompanying drawings for a detail description of a stopping mechanism constructed according to this invention, as shown in Fig. 1, A designates the elevator car, B the plunger, and G one of the guides which runs upon a vertical way W as the car moves up and down. These parts may be of any of the ordinary or approved constructions, and need not be herein described at length.

Bolted to or otherwise secured to the way W is a track 10, and running on the track 10 is a grooved wheel 11 journaled on a stud carried by an arm 12 extending up from a rock-shaft 13.

As shown most clearly in Fig. 2, the track 10 is provided with bent or curved ends for turning the arm 12 as the elevator car approaches the ends of its run.

The plunger B extends down into a casing 14 to which water may be supplied through an inlet passage at the upper end of the casing. As shown in Fig. 2, the water coming through the inlet passage first passes through ports 15, and down around the space between the plunger B and its casing 14. At its lower end, the plunger B is pro-

vided with a piston P, and before the pressure will be admitted to act on the under side of the piston P the water must pass through ports 18 and down through the inside of the plunger. The ports 18 are normally opened but may be closed by slides 19 carried by a rod 20 extending up inside the plunger. The rod 20 passes through a stuffing-box 21 up through a pipe or sleeve, and is connected at its upper end to an arm 22 extending in to the inside of the plunger from the rock-shaft 13. By means of this construction when the elevator car approaches the top of its run the ports 18 will be automatically closed, preventing the passage of water below the piston P, and automatically bringing the car to rest. In the same manner, when the car is descending and approaches the bottom of its run, the ports 18 will be closed, and the flow of water out through the ports 18 will be stopped so as to also bring the elevator car to rest.

In some cases, it is desirable to provide an additional stopping mechanism for stopping the car at the bottom of its run, and this may be done by providing a sleeve 16 having a plunger at its lower end normally standing above the ports 15. The sleeve 16 is held in its normal lifted position by springs 17, said parts being arranged so that when the car engages the upper end of the sleeve, it will force the same down against the spring 17 to close the ports 15, providing an additional means for bringing the car to rest at the bottom of its run. In some cases, instead of having the stopping ports covered by slides, it is desirable to provide a form of construction which will be more positive in action. This can be done by providing conical valve-seats and conical valves which shut off the pressure, as illustrated in Figs. 3 and 4.

As shown in Fig. 3, the slotted track 100 is provided with oppositely curved ends 23 and 24. Running in the slot of the track 100 is a stud carried by the arm 12 of the rock-shaft 13, so that by means of this construction when the elevator reaches the top of its run, the rock-shaft 13 will be turned in one direction, and when the elevator reaches the bottom of its run, the rock-shaft 13 will be turned in the opposite direction. Extending in from the rock-shaft 13 is an arm 22 connected to the operating rod 20, which is provided at its lower end with conical valves 25 and 26.

The piston P at the lower end of the plunger is provided with a central passage 27 for receiving the conical valves 25 and 26, as the case may be, to close the ports 28, said valves closing with the pressure so as to form a more perfect shut-off than in the construction illustrated in Fig. 2.

I am aware that numerous other changes may be made in practicing my invention by those who are skilled in the art, without de-

parting from the scope thereof as expressed in the claims. I do not wish, therefore, to be limited to the constructions I have herein shown and described, but

What I do claim and desire to secure by Letters Patent of the United States is:—

1. In a hydraulic elevator, the combination with a cylinder and plunger, of a stuffing-box through which the plunger passes, an enlarged portion on the end of the plunger having water passages, a valve for closing said passages, and a valve stem adapted to be operated from without the cylinder and plunger. 75

2. In a hydraulic elevator, the combination of a casing, a plunger, a car secured to the plunger, means for admitting and exhausting water to the annular space between the casing and plunger to act on the end of the plunger, a valve mechanism carried by 85 the plunger, and means extending out through the plunger to actuate the valve mechanism.

3. In a hydraulic elevator, the combination of the casing, a plunger fitted in the top of the casing, a car carried by the plunger, 90 means for admitting and exhausting water to the annular space between the casing and plunger to act on the end of the plunger, a valve mechanism mounted at the lower end of the plunger, and means extending out 95 through the plunger for actuating the valve mechanism.

4. In a hydraulic elevator, the combination of the casing, a plunger fitted in the top of the casing, a car carried by the plunger, 100 means for admitting and exhausting water to the space between the casing and plunger to act on the end of the plunger, a piston or enlargement carried by the plunger at its lower end, a valve mechanism carried by the 105 plunger, and means extending out through the plunger for actuating the valve mechanism.

5. In a hydraulic elevator, the combination of a casing, a plunger fitted in the top of 110 the casing, a piston or enlargement secured to the lower end of the plunger, a valve mechanism for controlling the flow, and means extending up through the plunger for actuating the valve mechanism.

6. In a hydraulic elevator, the combination of the casing, a plunger fitted in the top of the casing, a car carried by the plunger, means for admitting or exhausting water to the top of the casing down around the plunger 120 to act on the end of the plunger, an enlargement or piston carried by the end of the plunger, a valve mechanism carried by the plunger for controlling the flow through or past said enlargement or piston, and means 125 extending out beyond the plunger for actuating the valve mechanism.

7. In a hydraulic elevator, the combination of a casing, a plunger fitted in the top of the casing, means for admitting or exhaust- 130

- ing water to the top of the casing down around the plunger to act on the end of the plunger, an enlargement or piston carried by the end of the plunger, a valve mechanism carried by the plunger for controlling the flow, and a valve actuating rod extending up through the plunger to the car.
8. In a hydraulic elevator, the combination of a casing, a plunger fitted in the top of the casing, an enlargement or piston carried by the end of the plunger, ports formed therein, a valve mechanism controlling said ports, and means extending up through the plunger for actuating said valve mechanism.
- 15 9. In a hydraulic elevator, the combination of a car, a plunger-casing, a direct acting plunger connected with the car and having a piston at its lower end, valves inside the plunger casing controlling the admission of water to act on the underside of the piston, and means for automatically actuating said valves to stop the car.
10. In a hydraulic elevator, the combination of an elevator car, a direct acting plunger connected therewith, a valve mechanism carried by the plunger for controlling the flow of water to act on the underside of the plunger, and means for automatically operating said valve mechanism to stop the car.
- 25 11. In a hydraulic elevator, the combination of an elevator car, a direct acting plunger connected therewith having a piston at its lower end, and ports for admitting water through the inside of the plunger to act on the underside of the piston, and means for automatically controlling said ports to stop the car.
- 30 12. In a hydraulic elevator, the combination of an elevator car, a direct acting plunger connected therewith, a valve mechanism, an operating rod therefor carried by the plunger, and means for shifting the actuating rod to close the valve mechanism and stop the car at the ends of its run.
- 45 13. In a hydraulic elevator, the combination of the elevator car, a direct acting plunger connected therewith, with a piston at its lower end, ports for admitting water through the inside of the plunger to act on the piston, a valve mechanism controlling said ports, and an operating rod to close the valve mechanism and stop the car at the ends of its run.
- 50 14. In a hydraulic elevator, the combination of the elevator car, the direct acting plunger connected therewith, a vertical track,
- a sliding-piece running thereon, and connections extending down inside of the plunger for automatically shutting off the water to stop the car at the ends of its run.
15. In a hydraulic elevator, the combination of the elevator car, the direct acting plunger connected therewith, means for shutting off the water to stop the car at the ends of its run, and operating connections therefor extending up inside of the plunger.
- 60 16. In a hydraulic elevator, the combination of the elevator car, the direct acting plunger connected therewith, and having a piston at its lower end, ports for admitting water through the inside of the plunger to act on the underside of the piston, shut-off valves for closing said ports, an operating rod extending up inside the plunger, a sliding piece or wheel connected to operate said rod, and a vertical track having inclined portions at its ends for automatically stopping the car at the ends of its run.
- 65 17. In a hydraulic elevator, the combination of the elevator car, a plunger casing having ports near its upper end for admitting the water supply thereto, a plunger mounted in said casing, and directly connected to the elevator car, and a slide arranged to be forced down to close the ports when the car reaches the bottom of its run.
- 70 18. In a hydraulic elevator, the combination of the elevator car, the plunger-casing having ports near its upper end for admitting the supply of water thereto, and a spring-supported sleeve, said parts being arranged so that the spring-supported sleeve will be forced down to cover the ports when the car reaches the bottom of its run.
- 75 19. In a hydraulic elevator, the combination of the elevator car, a plunger-casing having ports for admitting the water supply near its upper end, a valve mechanism located within the plunger casing and having connections for automatically stopping the car at the ends of its run, and a vertically movable slide for covering the ports near the upper end of the casing to provide additional means for stopping the car at the bottom of its run.
- 80 In testimony whereof I have hereunto set my hand, in the presence of two subscribing witnesses.
